(57) **CLAIM**

The ornamental design for a tool bit carrier, as shown and described.

DESCRIPTION

FIG. 1 is an isometric view from the lower right front of a tool bit carrier including my new design, wherein tool bits shown in broken line are included merely for illustrative purposes and form no part of the claimed design;

FIG. 2 is a front elevational view thereof;

FIG. 3 is a right side elevational view thereof, the left side elevational view thereof being a mirror image of FIG. 3;

FIG. 4 is top plan view thereof;

FIG. 5 is a bottom plan view thereof;

FIG. 6 is a rear side elevational view thereof; and,

FIG. 7 is an isometric view thereof taken from the lower right front.
